CIGARETTE LIGHTER

Jean-Marie M. Paroty, Mauregard, France, assignor
to Societe Franco-Hispano-Americaine, Saint-Gratien,
France

Filed Oct. 12, 1972, Ser. No. 296,760

Term of patent 14 years

Int. Cl. D27—05

U.S. Cl. D48—27 R

Fig. 1.

Fig. 2.

Fig. 3.

Fig. 4.

Fig. 6.

FIG. 1 is a side elevational view of a first embodiment of the cigarette lighter, showing my new design, shown in open position;

FIG. 2 is a side elevational view of the lighter of FIG. 1, shown in closed position;

FIG. 3 is an elevational view of a second embodiment of my new design, shown from a different side;

FIGS. 4 and 5 are perspective views of the second embodiment of my new design, showing it in open and closed positions respectively; and

FIG. 6 is a top plan view of the lighter of FIG. 1.

I claim:

The ornamental design for a cigarette lighter, as shown and described.
